[57] CLAIM

The ornamental design for a toy tilt-bed trailer, as shown and described.

DESCRIPTION

FIG. 1 is a side elevational view of a toy tilt-bed trailer, showing my new design;

FIG. 2 is a top plan view thereof;

FIG. 3 is a bottom plan view thereof;

FIG. 4 is a rear elevational view thereof;

FIG. 5 is a front elevational view thereof; and,

FIG. 6 is a top perspective view thereof; and,

FIG. 7 is another side elevational view thereof, showing the design in an alternate position.
